UNITED STATES PATENT OFFICE

2,481,305

APPARATUS FOR DRYING BAGASSE

Charles W. Fuller, Clewiston, Fla.

Application October 4, 1945, Serial No. 620,366

5 Claims. (Cl. 110—7)

1

My invention relates to a process of drying wet fuel and the apparatus employed therefor. The main object of the invention is drying bagasse, that is sugar cane from which the sugar containing juice has been removed, but in general the process is applicable to drying other material to be used for fuel, as for instance wood refuse, bark, sawdust and the like. In the following the term "bagasse" generally used herein is meant to include also other material requiring drying before use as fuel, or for any other purpose: i. e. Celotex is made from bagasse, and bagasse may be used for paper making.

One embodiment of the invention is illustrated more or less diagrammatically in the accompanying drawings, wherein

Figure 1 represents a front elevation of the apparatus used and

Figure 2 is a side elevation thereof seen from the right side of Figure 1 as erected in a building of a drying plant.

Figure 3 is a top plan view of the drying equipment in Figure 1 and 2.

Figure 3a is a fragmentary plan view of Figure 4 of the tower and the inclined conveyor.

Figure 4 is a vertical section and part elevation of said tower showing the centrifugal mechanism.

Figure 5 is a fragmentary view in larger vertical section of the top portion of the heated drying tower showing the collecting means for moist gases.

Figures 6 and 7 are respectively a top plan view and a side elevation of a revolving cone used in the drying tower.

Figure 8 is a section of the inclined conveyor for feeding raw material into the top of the drying tower, and

Figure 9 is a diagrammatic sketch of the entire apparatus illustrating the progress of the bagasse through the system.

The basic features of the process consist in passing the bagasse, or other wet fuel, by means of a conveyor to the top of a tower through which it falls. In its fall it encounters a strong current of flue gas or pre-heated air moving in the opposite direction or upwardly in the tower. The tower contains a number of baffles so placed as to break the fall of the material into a series of cascades through which the hot gas passes, being drawn out of the top by means of an exterior exhaust fan. Part of the fines are also removed by this fan and later separated by another exterior fan as will be herein described. The material passing to the bottom of the tower is fed to a hammer mill or other similar device, if it is neces-

2

sary to further reduce the size of the particles, and to another fan which also draws a strong current of hot flue gas or preheated air through the hammer mill and discharges the gas and material to another cyclone separator and thence to another conveyor for delivery into the furnaces.

In the different figures, the same numerals correspond to the same details. Numeral 1 represents the upper strand of an endless supply conveyor which is used to bring the bagasse, or other wet material, from the mills to the furnace 5 with boilers 8 where the drying plant is located. The furnace 5 is usually arranged in batteries and the conveyor passes over the whole battery. It first passes the furnace or furnaces on the upper strand 1 in the direction of arrow X, Figure 1, then the material is dropped onto the lower strand 2 of the conveyor, running oppositely, in direction of arrow Y, via a gate 1b subsequently dropped through the gates 3, 3 into chutes 4, 4 which deliver the bagasse directly into the furnace 5, 5. In this case two furnaces have been shown but there may be any number, one, two, or three furnaces to a boiler.

25 In order to dry the material it is carried past the gates 3, 3, which then must be closed and to gate 6 which when opened drops the material thru chute 6a which delivers it directly onto the heated inclined conveyor or elevator 7 which is operated by the motor 48. This elevator delivers the material at the top of the drying tower 31 through a chute 59.

30 In the drying tower 31 is shown a series of baffles consisting of revolving cones 32 carried by supporting spiders, and of inverted stationary cones 31. The revolving cones and spiders are supported on a shaft 33 at top and bottom and passing up through the center of the tower 31 and may be revolved at any predetermined speed in order to delay the passage of the bagasse, break up any adhering lumps, and permit more complete contact with the upward current of hot gases, thereby removing more moisture.

35 The upper surface of the revolving cones 32, see Figure 6, 7, carries curved vanes 32a secured on the upper surface of each cone which is attached to the axial shaft 33 carried in a suitable bearing 35 here shown at the top of the tower 31 and driven by bevel gears enclosed in the housing 34 furnishing needed lubrication for the gears. One or more lower bearings 36 are provided for the lower end of the shaft 33, held by horizontal arms in the tower, see Figure 4, to prevent vibration.

40 45 50 55 Between each two revolving cones 32 is pro-

vided a fixed inverted baffle cone 37, open top and bottom, see Figure 4, and made of sheet metal. These baffle cones serve to retard the downward passage of the bagasse or other material thru the tower. Several circular rows of perforations 37a are shown to permit the rising current of drying gas to pass and clean the cone surface.

The hot flue gases to heat the drying tower 31 are drawn from the breeching 10, through the pipes 11 and 12 by means of the exhaust fan 14 actuated by motor 14a, also drawing the gases from the top of the dryer through pipe 13. The moisture laden gases and fines are delivered by pipe 15 to cyclone separator 16. (See Figures 1 and 2.)

The inclined conveyor or elevator 7, best seen in Figures 3, 4 and 8 is carried on a pair of parallel channel irons 40 reaching from beneath chute 6a of conveyor 2 to the upper end of the drying tower 31, where the ends are firmly anchored and between and beneath said channels is secured a perforated floor plate 41. At each end of the pair of channels is furnished a transverse shaft 42 for sprocket wheels 43 over which run the endless elevator chains connected by transverse slats 44 of hardwood or the like. These slats slide up along the floor plate 41 on the upper run or strand carrying the raw material with it, while on the lower run they are supported on longitudinal angle bars 45 suitably suspended from the channel bars 40. A nest of steam pipes 46 for supplying heat to dry the material is supported under the angle bars 45. The conveyor chain 44a is run by a belt or chain drive, a sprocket 47 which is carried on the end of the upper shaft 42 and actuated by a motor 48 with a speed reducer 48a.

The material carried up by the inclined conveyor or elevator 7, is dumped from the upper run or strand thereof into a fixed chute 50, inclined about 60° from the horizontal and then dumped over the top cone 32 in the drying tower 31. This chute 50 has a flaring upper skirt 50a, until it reaches the side of the tower where its lower portion tapers and curves as seen in Figures 4 and 5. Opposite the same is shown a fixed baffle plate or guide 51 for directing the rising gases and moisture from the material to the exhaust hood 13a to be led off from the tower 31 thru pipe 13 aided by the exhaust fan 14.

By means of an intermediary shaft 52 and chain drives 53 and 54 power is transferred from motor 48 and conveyor shaft 42 to the bevel gear shaft 35a, whereby the axial tower shaft 33 with its several revolving cones 32 is rotated.

All the heavier material which falls to the bottom of the tower after having passed all baffles in tower 31 is fed into the hammer mill 18 if further disintegration is necessary. However, if any treatment by hammer mill 18 is unnecessary, the material goes directly to the fan 20 which also draws hot gases through pipes 19 and 19b, from pipes 11 and 12. The material from fan 20 is then delivered through pipe 21 to the cyclone separator 22. More moisture is thus extracted from the Bagasse by this process. All pipes are exteriorly heat insulated to prevent cooling of the hot gases and condensation of the moisture carried by them.

A horizontal conveyor 23 of any suitable construction driven by motor 28a is provided for passing the coarse material and/or the fines delivered thereto via feed pipes 60 from the separators 16 and 22 to feed the material through

the gates 24 to feeders 25 either to the conveyor 1 or directly by chutes 26 and 4 to the furnaces 5. If desired, the coarse material and fines may be delivered directly to bags (not shown) through branch pipes 62 communicative with the pipes 60 by means of suitable gates 64.

Other pipes 27 and 27a are provided to conduct the fines, separated by the cyclone separators 16 and 22. Said pipes furnish an exit 10 for the dried fines, from the tops of the separators to the exhaust fan 28, Figures 1 and 2, which delivers them through the pipe 29 to the burner 30 where fresh air is supplied for the combustion of the fines.

15 The operation of the plant for drying bagasse, or other fuel material is the following, special reference being had to Figure 9:

The bagasse enters from the sugar mill upon the conveyor strand 1, which passes in front of one or more boilers to some point beyond the furnace where it is dropped to the lower strand 2 via gate 1b, whence it is usually fed by means of the gates 3 through the chute 4 direct into the furnace 5. This method of operation is followed until the furnaces are heated and hot gases passing out through the stack.

The gates 3 are then gradually closed and the gate at 6 opened to permit the bagasse to fall into the feeder chute 6a and onto the inclined conveyor or elevator 7 which may be heated by steam pipes or hot gases. This elevator 7 is operated by the motor 48 and delivers the bagasse near the top of the tower 31 onto the chute 50.

When the bagasse enters the top of the drying tower 31 and falls down through the same it encounters a strong upward current of hot flue gases, either from the breeching 10 leading to the chimney, or from the chimney direct if this is found to be easier. These hot gases are carried into the tower 31 by pipes 11 and 12 by means of the exhaust fan 14 drawing the gas from the top through pipe 13. The moisture laden gas and some fines carried off by the suction of the fan 14 are delivered by pipe 15 to the separator 16.

In passing downward through the tower 31 the bagasse encounters a series of revolving cones 32, which can be revolved as already described, and baffle cones 37 which are fixed to the sides 50 of the tower 31. The revolving cones 32, with vanes 32a on the top are arranged to give the bagasse a centrifugal motion as it is thrown off.

The coarse material then passes out through the bottom of the tower 31 and may be conducted via the branch 19c of the pipe 19 directly to the hammermill 18 to completely break up the coarse material in order to extract all moisture. If desired, the coarse material may be conducted through pipe 19 directly to the exhaust fan 20 to be blown through pipe 21 up to the cyclone separator 22.

From the separators 16 and 22, the coarse and fine material may be led through pipe 60 onto the conveyor 23 and from the latter through gate 24 and feeders 25 to be delivered onto the conveyor 1 for a repetition of the cycle mentioned hereinabove. If desired, the material may be led via gate 64 to the conduits 62 and thence to bags (not shown). Also, if desired, the material may be led from the feeders 25 by chutes 4 and 26 directly to the furnace 5.

Alternately, the fines separated by the cyclone separators may be conducted through the pipes 75 27 and 27a to the exhaust fan 28 which delivers

them to the burner 38 where fresh air is supplied for the combustion of the fines.

It is to be understood that the invention as here disclosed is not limited to the details here described but that the same may be varied without departing from the spirit of the invention as defined by the subjoined claims. So for instance the drive of shaft 33 for the revolving cones 32 may be applied from the bottom thereof instead of the top. Likewise a fan may be used for driving air upwards thru the tower instead of exhausting the gases by a fan.

I claim:

1. In an apparatus for drying wet material of the bagasse type for use as a fuel or in the manufacture of board and paper, comprising a drying tower consisting of a vertical tubular casing, means for discharging the bagasse into the upper portion of the tower, means for drawing hot air and gases upwardly through the tower from the bottom thereof and discharging the same at the top, a series of spaced alternating stationary and revolving baffles arranged in said casing and comprising inner conical baffles, a shaft rotatably mounted axially through the casing and to which said inner baffles are secured, means for rotating the shaft, said inner baffles having their peripheral edges spaced from the wall of the casing, outer frusto-conical baffles arranged alternately between the inner baffles and extending from said wall inwardly beneath the peripheral edges of the inner baffles in inverted position inclined inwardly with their small ends open at the bottom to receive the material from the inner baffles in cascades and dropping downwardly through the tower from one cone to the other, said inner baffles having curved vanes thereon to give the bagasse a centrifugal motion as it is thrown off from the revolving baffles, said outer baffles receiving the material from the inner baffles and discharging the same at the bottom upon the inner baffles therebeneath, said hot air and gases passing upwardly in a tortuous path at the inside of the outer baffles and outwardly of the inner baffles within the casing and prevented from passing between the outer baffles and the casing, means to prevent adherence of the material upon the surfaces of the outer baffles, the fines passing off with the heated air and gases at the top, a grinder receiving the material at the bottom of the tower, means for exhausting and conveying said material therefrom, means for supplying hot air and gases to said grinder and latter means, means for conveying the dried material from said latter means for discharge to the furnace or storage, and a separator adapted to receive the fines together with the hot air and gases from the top of the tower for discharge to a furnace and also adapted to receive the bagasse from the conveyor leading from the bottom of the tower after passing through the grinder for discharge to the furnace or storage.

2. The combination with a furnace of an apparatus for drying wet material of the bagasse type for use as a fuel, for making paper or the like, said apparatus comprising a drying tower, a separator, a grinder, means for transferring said material into said apparatus from a source of supply, said transferring means consisting of a feeder for the drying tower for conveying the material into the top thereof, means for drawing a current of hot air and gases from the breeching of the furnace upwardly through the tower from the bottom thereof for discharge at

the top, said tower having inner and outer baffles alternating from the top thereof, providing a tortuous passage between the baffles through which the material is dropped from the top of the tower, the inner baffles comprising cones mounted for rotation and spaced from the wall of the tower, means for rotating said cones, said cones sloping outwardly, the outer baffles comprising inverted frusto-conical members extending from the wall of the tower and sloping inwardly and downwardly beneath the inner cones and having restricted discharge openings at the bottom beneath the outer portions of the inner cones to provide a tortuous space for passage of the material through the tower between the baffles for exposure to the heated air and gases passing upwardly through the tower, means for dislodging and preventing adherence of the material to the baffles, a grinder at the bottom of the tower to receive the material, means extending from the grinder for conveying the material from the grinder, means for supplying heated air and gases to the latter means for additionally drying the material, a separator connected to the means for drawing the hot air and gases upwardly through the tower to the top thereof for receiving the fines from the material therewith, and means for discharging and feeding the fines and other bagasse material to the furnace or for conveyance to storage.

3. The combination with a furnace of an apparatus for drying wet material of the bagasse type for use as a fuel, for making Celotex, paper or the like, said apparatus comprising a drying tower arranged vertically and provided with a tubular casing having a series of alternately arranged stationary and revolving baffles therein in spaced relation, said stationary baffles extending from the wall of the tower inwardly and open at the bottom to receive the material from the revolving baffles and discharge onto the same, means for revolving said revolving baffles, said baffles providing a tortuous passage for material dropping through the tower, means for transferring said material from a sugar mill or other source of supply to and over the furnace, a conveyor extending from said transferring means to the top of the tower for discharge thereinto, a chute in the tower receiving the material from the conveyor for discharge onto the baffles, means for supplying heated air and gases in a stream to the bottom of the tower and upwardly therethrough, means for discharging said heated air and gases at the top of the tower after passing through the material dropping between the baffles to the bottom thereof and for conveying the fines from the material a separator connected to the latter means for receiving said hot air and gases and fines therefrom, means for discharging said fines into the furnace, means at the lower end of the tower for conveying the dried material therefrom and conveying the same upwardly for discharge to the separator, into the combustion chamber of the furnace or to storage.

4. In combination with a furnace of an apparatus for drying bagasse comprising a drying tower, a separator, means for initially conveying the bagasse from a source of supply to the furnace until heated and hot gases pass out of the breeching of the furnace to the stack thereof, means for conveying the material from the latter means to the top of the tower, a series of alternating stationary and revolving baffles arranged in the tower, said tower comprising a tubular casing, the stationary baffles extending inwardly from the casing to prevent the passage of hot air and

gases therebetween, said bagasse adapted to cascade between the baffles in dropping downwardly through the tower, means for supplying heated air and gases to the bottom of the tower and connected to the breeching of the furnace, means for causing a rising countercurrent of hot air and gases upwardly through the tower for drying the descending stream of bagasse downwardly there-in between the baffles and for discharging the same together with the fines from the bagasse to the separator for subsequent delivery to the furnace, and means for conveying the dried bagasse from the bottom of the tower for feeding into the combustion chamber of the furnace or to storage.

5. In combination with a furnace of an apparatus for drying bagasse comprising a drying tower, a separator, means for initially conveying the bagasse from a source of supply to the furnace until heated and hot gases pass out of the breeching of the furnace to the stack thereof, means for conveying the material from the latter means to the top of the tower, a series of alternating stationary and revolving baffles arranged in the tower, said tower comprising a tubular casing, the stationary baffles extending inwardly from the casing to prevent the passage of hot air and gases therebetween, said bagasse adapted to cascade between the baffles in dropping downwardly through the tower, means for supplying heated air and gases to the bottom of the tower and connected to the breeching of the furnace, means for causing a rising countercurrent of hot air and gases upwardly through the tower for drying the descending stream of bagasse downwardly there-in between the baffles and for discharging the same together with the fines from the bagasse to the separator for subsequent delivery to the furnace, a hammer mill connected to the bottom of the tower to receive the bagasse dropping there-through, means connected to the hammer mill

5

10

receiving a supply of hot air and gases from the same source as the tower, a suction fan for drawing said hot air and gases through said hammer mill and for discharging and elevating the partially dried wet material to said separator for removing moist gases therefrom and delivering the same to the separator for subsequent discharge to the furnace or to storage at the transferring means, and means for discharging the fines from the separator to the combustion chamber of the furnace.
